Primary Examiner — Keli L Hill(74) *Attorney, Agent, or Firm* — QuickPatents; Kevin Prince(57) **CLAIM**

I claim the ornamental design for an interchangeable joystick, as shown and described.

DESCRIPTION

FIG. 1 is a perspective view of an interchangeable joystick, showing my new design;

FIG. 2 is a bottom plan view thereof;

FIG. 3 is a left-side elevational view thereof, the right-side elevational view, front elevational view, and rear elevational view all being identical thereto; and,

FIG. 4 is a top plan view thereof.

The broken lines seen in FIG. 2 immediately adjacent the structure line represent the bounds of the claimed design and forms no part of the claimed design.
